CLAIM

The ornamental design for an electrical ground clip for meter panel, as shown and described.

DESCRIPTION

FIG. 1 is a right side, top and front perspective view of an electrical ground clip for meter panel, showing my new design;

FIG. 2 is a partly-fragmented left side elevational view thereof;

FIG. 3 is a partly-fragmented bottom plan view thereof;

FIG. 4 is a top and front perspective view showing details of the electrical ground clip illustrated in FIG. 1;

FIG. 5 is a top plan view thereof;

FIG. 6 is a front elevational view thereof;

FIG. 7 is a right side elevational view thereof;

FIG. 8 is a left side elevational view thereof;

FIG. 9 is a rear elevational view thereof;

FIG. 10 is a bottom plan view thereof;

FIG. 11 is a sectional view taken along line 11—11 of FIG. 5;

FIG. 12 is a top and front perspective view showing details of an electrical ground clip according to a second embodiment of my new design;

FIG. 13 is a top plan view thereof;

FIG. 14 is a front elevational view thereof;

FIG. 15 is a right side elevational view thereof;

FIG. 16 is a left side elevational view thereof;

FIG. 17 is a rear elevational view thereof; and,

FIG. 18 is a bottom plan view thereof.

The broken line showing is included for the purpose of illustrating environmental structure only and forms no part of the claimed design.
